CLAIM

The ornamental design for a deck box, as shown and described.

DESCRIPTION

FIG. 1 is a front perspective view of a deck box embodying the principles of the present invention;

FIG. 2 is a rear perspective view of the deck box;

FIG. 3 is a side view of the deck box as taken from the right-hand side of FIG. 1, the left-hand side view being a mirror image thereof;

FIG. 4 is a top view of the deck box;

FIG. 5 is a front view of the deck box;

FIG. 6 is a rear view of the deck box;

FIG. 7 is a bottom view of the deck box; and,

FIG. 8 is a front perspective view of the deck box similar to FIG. 1, with the box shown in the opened position.
